UNITED STATES PATENT OFFICE

WASYL WASYLUK, OF PHILADELPHIA, PENNSYLVANIA

DESIGN FOR A BASKET

Application filed June 13, 1931. Serial No. 40,204. Term of patent 14 years.

To all whom it may concern:

Be it known that I, WASYL WASYLUK, a citizen of the United States of America, residing at Philadelphia, in the county of Philadelphia and State of Pennsylvania, have invented a new, original, and ornamental Design for Baskets, of which the following is a specification, reference being had to the accompanying drawings, forming part thereof.

I claim:

The ornamental design for a basket, as shown.

WASYL WASYLUK.
